UNITED STATES PATENT OFFICE.

JOHN D. IHLDER, OF YONKERS, NEW YORK, ASSIGNOR TO OTIS ELEVATOR COMPANY, OF EAST ORANGE, NEW JERSEY, A CORPORATION OF NEW JERSEY.

MOTOR CONTROL.

SPECIFICATION forming part of Letters Patent No. 767,691, dated August 16, 1904.

Application filed May 5, 1902. Serial No. 106,072. (No model.)

To all whom it may concern:

Be it known that I, JOHN D. IHLDER, a citizen of the United States, residing at Yonkers, in the county of Westchester and State of New York, have invented certain new and useful Improvements in Motor Control, of which the following is a specification.

My invention relates to motor control; and its objects are primarily to enable an electric motor to be automatically controlled in a simple and convenient manner which reduces the liability of injury to the motor and prevents the starting-current from rising beyond a predetermined amount.

Further objects of my invention will hereinafter appear; and to these ends my invention consists in the system of motor control devised for carrying out the above objects and having the general mode of operation substantially as fully described and shown in the accompanying specification and drawings, in which—

Figure 1 is a diagrammatic view showing circuits and apparatus embodying one form of my invention, and Fig. 2 is a diagrammatic view showing a modified form of my invention.

Referring to the drawings, A represents a motor, which may be of any suitable type, but shown in this instance as a shunt-wound motor adapted to be connected in circuit with the supply-mains (indicated by + and —) and provided with a series field-winding B and a shunt-field C, the shunt-field being connected to the mains at the points *a* and *b*. A suitable switch D is arranged to control the admission of current to the motor-armature, and the throwing of the switch-lever *c* into contact with contacts *d* and *e* will first complete the circuit of the electromagnet E, connected across the mains and controlling contacts *f* in the main armature-circuit. The energizing of magnet E closes contacts *f* and completes the circuit to the motor through resistances F and G and the series field-winding B, which also includes, preferably, a portion of the starting resistance H for purposes of regulating. The completion of the armature-circuit throws

the full-line potential on magnet I, shown connected across the line from a point *g* to the switch D, causing magnet I to actuate its core *i* and close circuit between contacts 4 and 5 and the insulated contact 6 and 7 on the core, thereby short-circuiting a portion of resistance F and completing a circuit through the shunt-winding *h* of the doubly-wound magnet I. The doubly-wound magnets 1, 2, and 3 are assumed to be differentially wound, being provided with shunt-windings *h*, connected in parallel to each other and in shunt to the main line, and also provided with windings *j* in series with the line, the series windings being of insufficient strength, however, to move a core *h* even with maximum current. After magnet I has closed its contacts and short-circuited a portion of resistance F the current will have increased sufficiently to start the motor under all loads, and although but one magnet I is illustrated for the sake of simplicity in the diagram of Fig. 1 any desired number of magnets I may be used to short-circuit the resistance F in a series of steps to admit the maximum permissible strength of starting-current. The starting of the motor cuts down the armature-current and the strength of the series winding *j* of magnet I, while the shunt-winding *h* of said magnet gradually comes up to maximum strength due to the difference of potential between the points *l* and *a* on the line between which the shunt-winding is connected, this difference of potential not being quite the full-line potential, since the point *l* is taken between the resistance F and the motor, which is the preferable arrangement, because the fall of potential through the resistance F aids in regulating the magnet I, the fall of potential being greater with the maximum current which causes the closing of the contacts of magnet I than with a reduced current. As the current decreases and as the resistance F decreases with a plurality of such starting-magnets I or with the one magnet shown the shunt-coil *h* of magnet I becomes strengthened, while the series coil *j* becomes weakened until a point is reached where the core *h* is actuated to close circuit between contacts 8 and 9 and insulated

contacts 10 and 11 on the core, thereby short-circuiting more of the starting resistance F and completing the circuit of the shunt-coil h of magnet 2. The short-circuiting of resistance F again increases the current to a maximum, from which it is reduced by the further increase of armature speed, thus repeating the operation for magnets 2 and 3 as described for magnet 1, until finally circuit is closed 10 between contacts 12 13 and 14 15 of magnet 2 and contacts 16 17 and 18 19 of magnet 3, whereby all of the resistance and the series field-winding B are short-circuited.

It will be seen that as the magnets 1, 2, and 15 3 operate the series windings j are short-circuited in turn, and when magnet 3 operates to close contacts 16 and 18 a circuit is completed to a third winding p on magnet 3 and to a magnet q , the circuit of magnets p and q 20 being connected, as shown in this instance, across the line. Coil p operates as a holding-coil to maintain contacts 16 17 and 18 19 closed, and magnet q actuates contacts 20 to break the circuit of all the shunt-windings h , so that 25 they do not consume current after the motor has started.

According to my invention the current cannot rise beyond a predetermined amount, for any increase of current beyond the predetermined amount in starting so strengthens a series winding j that the operation of cutting out resistance does not continue until the current has again reduced to the desired amount. In other words, my apparatus is so constructed 30 that the amount of starting-current which can be admitted is limited, for when the starting-current rises beyond a predetermined amount the operation of cutting out resistance will be suspended.

40 To stop the motor, the lever c is moved to break circuit with contacts d and e , contact d being longer than e , so that circuit is broken with contact e first, thus breaking the circuit of magnet q first and throwing the resistance 45 back into circuit before magnet E is deenergized to break the armature-circuit.

It is not necessary that each shunt-winding h should have its circuit separately controlled, as described in connection with Fig. 1, nor 50 that there should be a magnet I or magnets provided for the preliminary operation of admitting the maximum starting-current, for the maximum starting-current may be admitted at once on the first step, if desired, as 55 provided for in Fig. 2.

In Fig. 2 the shunt magnet-windings h of magnets 1, 2, and 3 are shown in series with each other and connected to the line in such manner that circuit through them is always 60 completed when switch D is closed. The series windings j of these magnets are arranged in the same manner as before, and this whole construction requires a more exact adjustment than that shown in Fig. 1 to obtain the same 65 operation. The shunt and series windings on

magnets 1, 2, and 3 are differentially wound, as before, and the adjustment can be made by winding the magnets all to the same strength and then setting the armatures 21, 22, and 23 at different distances from the cores k , so that 70 armature 21 of magnet 1 will be attracted with less strength of magnet than will attract the armature 22 of magnet 2, and the armature 22 of magnet 2 will be attracted on less strength of magnet than will attract the 75 armature 23 of magnet 3, or else the magnets may be wound to different strengths with the armatures 21, 22, and 23 arranged at the same distances from the cores k . In this latter case the shunt-windings h may decrease in 80 strength from magnets 1 to 3, or else the series windings j may increase in strength from magnets 1 to 3, as may be desired, so that magnet 1 always operates to attract its armature on less magnet strength than magnet 2 85 and magnet 2 operates on less magnet strength than magnet 3, the whole operation of the apparatus shown in Fig. 2 being substantially the same as that shown in Fig. 1.

Without limiting myself to the construction 90 shown and described, I claim—

1. The combination with a motor having an armature, of a controlling means therefor dependent for its operation upon the differential action of the potential and current of the motor-armature, substantially as set forth.

2. The combination with a motor having an armature, of a step-by-step controlling means comprising an actuating mechanism for each step dependent for its action upon the potential and current of the motor-armature, substantially as set forth.

3. The combination with a motor having an armature, of a step-by-step controlling means comprising an actuating mechanism for each 105 step dependent for its action upon the differential action of the potential and current of the motor-armature, substantially as set forth.

4. The combination of supply-mains, a motor-armature, a potential-reducing device, and regulating means for said device connected in series between said mains and other regulating means coöperating with the said aforesaid regulating means, connected in a circuit in parallel with said armature and in series with 115 said device, substantially as set forth.

5. The combination of supply-mains, a motor-armature, a potential-reducing device, and regulating means for said device connected in series between said mains and other regulating means coöperating differentially with the aforesaid regulating means, connected in a circuit in parallel with said armature and in series with said device, substantially as set forth.

6. The combination of supply-mains, a motor-armature, a resistance, and regulating means for said resistance connected in series between said mains and other regulating means coöperating with the aforesaid regulating 125 130

- means, connected in a circuit in parallel with said armature and in series with said resistance, substantially as set forth.
7. The combination of supply-mains, a motor-armature, a resistance, a regulating means for said resistance connected in series between said mains and other regulating means co-operating differentially with the aforesaid regulating means, connected in a circuit in parallel with said armature and in series with said resistance, substantially as set forth. 70
8. The combination with a motor having an armature, of a controlling means for said motor comprising an actuating-electromagnet, said electromagnet having a winding depending for its energy upon the potential of the motor-armature and another winding dependent for its energy upon the current of said armature, substantially as set forth. 75
- 20 9. The combination with a motor having an armature, of a controlling means for said motor comprising an actuating-electromagnet, said electromagnet having differential windings, one of which depends for its energy upon the potential of the motor-armature and another of which is dependent for its energy upon the current of said armature, substantially as set forth. 80
- 25 10. The combination with a motor having an armature, of a step-by-step controller therefore, an electromagnet for each step, each of said electromagnets having differentially-wound coils, of which one depends for its energy upon the current and the other upon the potential of said armature, substantially as set forth. 85
- 30 11. The combination with a motor having an armature, of a resistance, supply-mains and a controller for cutting out said resistance step by step comprising a series of electromagnets, each of which has differentially-wound coils, one of which is connected in series with said armature and resistance between said mains, the other being connected in a circuit in parallel with said armature and in series with the armature-resistance, substantially as set forth. 90
- 45 12. The combination with a motor having an armature, of a step-by-step controlling means comprising a mechanism for each step dependent for its operation upon the potential and current of the motor-armature and upon a mechanism of a preceding step, substantially as set forth. 95
- 50 13. The combination with a motor having an armature, of a step-by-step controlling means comprising a mechanism for each step dependent for its operation upon the differential action of the potential and current of the motor-armature and upon a mechanism of a preceding step, substantially as set forth. 100
- 55 14. The combination with a motor having an armature, of a step-by-step controlling means comprising an electromagnet for each step having windings, one of which windings depends for its energy upon the current of the 105
- 60 15. The combination with a motor having an armature, of a step-by-step controlling means comprising an electromagnet for each step having differential windings, one of which windings depends for its energy upon the current of the motor-armature the other of which windings is dependent for its energy upon the potential of said armature, the circuits of said windings being controlled by an electromagnet of a preceding step, substantially as set forth. 110
- 65 16. The combination with a motor having an armature, of a step-by-step controlling means comprising a potential-reducing device, mechanism for each step, each of said mechanisms having a coil dependent for its energy upon the potential of said armature, and connections whereby the said mechanisms successively connect the coils of succeeding mechanisms to different points of said potential-reducing device, substantially as set forth. 115
- 70 17. The combination with a motor having an armature, of a step-by-step controlling means comprising a mechanism for each step and a potential-reducing device, each of said mechanisms having a potential-coil dependent for its energy upon the potential of said armature and a current-coil dependent for its energy upon the current of said armature, and connections whereby the said mechanisms successively connect the potential-coils of succeeding mechanisms to different points of said potential-reducing device, substantially as set forth. 120
- 75 18. The combination with a motor having an armature, of a step-by-step controlling means comprising a mechanism for each step and a potential-reducing device, each of said mechanisms having a potential-coil dependent for its energy upon the potential of said armature and a current-coil dependent for its energy upon the current of said armature, said potential and current coils being differentially wound, and connections whereby the said mechanisms successively connect the potential-coils of succeeding mechanisms to different points of said potential-reducing device, substantially as set forth. 125
- 80 19. The combination with a motor having an armature, of a step-by-step controlling means comprising a mechanism for each step, and a resistance, each of said mechanisms having a coil dependent for its energy upon the potential of said armature and connections whereby the said mechanisms successively connect the coils of succeeding mechanisms to different points of said resistance, substantially as set forth. 130
- 85 20. The combination with a motor having an armature, of a step-by-step controlling

means comprising a mechanism for each step and a resistance, each of said mechanisms having a potential-coil dependent for its energy upon the potential of said armature and a current-coil dependent for its energy upon the current of said armature, and connections whereby the said mechanisms successively connect the potential-coils of succeeding mechanisms to different points of said resistance, substantially as set forth.

21. The combination with a motor having an armature, of a step-by-step controlling means comprising a mechanism for each step and a resistance, each of said mechanisms having a potential-coil dependent for its energy

upon the potential of said armature and a current-coil dependent for its energy upon the current of said armature, said potential and current coils being differentially wound, and connections whereby the said mechanisms successively connect the potential-coils of succeeding mechanisms to different points of said resistance, substantially as set forth. 20

In testimony whereof I have signed my name to this specification in the presence of two subscribing witnesses. 25
